UNITED STATES PATENT OFFICE.

CLARENCE JOSEPH BOYLAND, OF INDIANAPOLIS, INDIANA.

INSULATOR-PIN.

1,022,121.

Specification of Letters Patent.

Patented Apr. 2, 1912.

Application filed November 8, 1911. Serial No. 659,216.

To all whom it may concern:

Be it known that I, CLARENCE J. BOYLAND, a citizen of the United States, residing at Indianapolis, in the county of Marion and 5 State of Indiana, have invented a new and useful Insulator-Pin, of which the following is a specification.

This invention relates to insulator pins, and has for its general object to provide an 10 improved pin which will eliminate or remedy the objections and defects existing in the employment of the ordinary wooden or other pin of this character in common use; and to provide a simple, inexpensive, 15 durable, practical and thoroughly efficient device of this character.

It is the specific object of this invention to provide a pin of this character stamped 20 from sheet metal to form a body having a resilient transversely contractible and expansible shank at one end and a transversely contractible and expansible threaded stem at the other end thereof, the shank being adapted to engage in the socket of a cross 25 arm of the usual telephone or telegraph pole, or the like, for the suspension of electric lines.

According to present practice, the insulator is supported by a wooden or metallic 30 pin having its shank inserted into a socket in the cross arm, this resulting in a number of objections and defects, among these being the tendency of the cross arm to rot or decay around the socket due to the moisture 35 in the vicinity of the pin thus loosening the pin, the tendency of the wooden pin to become broken or fractured, and in some pins the accidental breaking or fracturing of the insulator due to the expansion of the 40 pin. These and other defects and objections are well known in the art and need not be itemized at length.

The above defects and objection present 45 in the insulator pin in common use has prompted the invention of a pin better adapted for the purpose and eliminating or remedying many, if not all, of the existing objections and defects in pins of this character.

50 The result of the present invention is characterized by certain novel features of construction which will appear hereinafter and which are pointed out in the appended claims, reference being had to the accompanying drawing, wherein:

Figure 1 is an elevation of the pin as in

use, parts being broken away. Fig. 2 is an elevation of the insulator pin constructed in accordance with the present invention. Fig. 3 is a plan view of the blank from which the pin is formed.

Referring in detail to the drawing, wherein similar reference characters indicate similar parts, the blank from which the insulator pin is formed is designated at 12 comprising a plate of galvanized iron or other metal of suitable thickness and quality. This blank is stamped or formed into a shell pin comprising the body 6 having the shank 11 at one end thereof formed by 70 reducing the diameter of the pin and the threaded stem 5 at the other end thereof, said blank being bent longitudinally to bring the longitudinal edges adjacent each other whereupon the pin is split longitudinally throughout the length thereof. The metal from which this pin is formed is of suitable resiliency and the edges thereof are spaced slightly apart, thus permitting the body, shank and stem to be yieldable transversely thereof or to be transversely contractible and expansible. The shank 11 is reduced in diameter to provide a shoulder 7 at the inner end thereof and is provided with a plurality of longitudinal slits 9 extending from the shoulder 7 to the outer end thereof forming a plurality of tongues 8 which have their adjoining edges spaced apart, the shell being thinner at the shank. These tongues being resilient provide an additional yielding or contraction and expansion of the shank 11 for the purpose to be hereinafter described. From the tongues 8 of the shank 11 are struck a plurality of 85 outwardly facing staggered spurs 10 which project away from the outer end of the shank.

To illustrate the application of the insulator pin, there has been shown in Fig. 1 a portion of the cross arm at 13 having the vertical socket 14 drilled therethrough as customary for the reception of the wooden or other pin, these cross arms being usually of wood. The shank of the pin is inserted into the socket 14 and being contractible or yieldable permits the same to be readily forced therein to bring the shoulder 7 of the pin against the upper side of the cross arm. Upon the shank being inserted into the socket 14 the spurs or teeth 10 engage in the socket to prevent the pin from being removed unless the tongues 8 are forced in.

wardly from the lower side of the cross arm. In this manner the pin is readily attached to the cross arm and is retained in position, the spurs or teeth 10 also holding the shoulder 7 tightly against the upper side of the cross arm.

The insulator is designated at 4, being of the usual type of construction, and the same is engaged on the stem 5 of the pin, and inasmuch as this stem is contractible and expansible it will be noted that the tendency to break or fracture the insulator is remedied or eliminated. It will also be noted that the slits 9 of the shank of the pin form passages from the exterior to the interior of the shank thus permitting the moisture in the vicinity of the socket to escape into the interior of the pin to facilitate the drying of the cross arm and therefore prevent the rotting or decaying thereof.

It is known that insulator pins have heretofore been formed of metal and I do not broadly claim a metallic or a hollow pin, but

25 What I do claim and desire to protect by Letters Patent is:-

1. An insulator pin comprising a one part sheet metal shell split longitudinally throughout its length with the edges spaced

apart whereby the pin as a whole is transversely contractible, one end of the pin being reduced in diameter to form a shank and a shoulder at the inner end thereof, the shell being thinner at the shank, the shank having a plurality of longitudinal slits extending from the shoulder to the outer end of the shank to form yieldable tongues which have their adjoining edges spaced apart, and a plurality of staggered spurs struck from the tongues which project away from the outer end of the shank.

2. An insulator pin comprising a one part sheet metal shell split longitudinally throughout its length, one end of the pin being reduced in diameter to form a shank and a shoulder at the inner end thereof, the shank having a plurality of longitudinal splits extending from the shoulder to the outer end of the shank to form yieldable tongues, and a plurality of spurs struck from the tongues.

In testimony that I claim the foregoing as my own, I have hereto affixed my signature in the presence of two witnesses.

CLARENCE JOSEPH BOYLAND.
